UNITED STATES PATENT OFFICE.

EDWARD T. CURRAN, OF DETROIT, MICHIGAN.

RADIATOR.

1,352,584.

Specification of Letters Patent. Patented Sept. 14, 1920.

Application filed June 22, 1918. Serial No. 241,326.

To all whom it may concern:

Be it known that I, EDWARD T. CURRAN, a citizen of the United States, residing at Detroit, county of Wayne, State of Michigan, have invented a certain new and useful Improvement in Radiators, and declare the following to be a full, clear, and exact description of the same, such as will enable others skilled in the art to which it pertains to make and use the same, reference being had to the accompanying drawings, which form a part of this specification.

My invention relates to radiators such as are used principally in automobiles for water cooling the engines thereof and it consists in the peculiar arrangement construction and combinations hereinafter specified and claimed.

In the drawings:

20 Figure 1 represents the radiator attached to an automobile.

Fig. 2 is a side elevation with the hood removed.

25 Fig. 3 is an elevation of the rear portion of the radiator looking from the front.

Fig. 4 is a sectional elevation of the upper portion of the radiator showing the arrangement of the connecting pipes through the sections of the radiator.

30 Similar letters refer to similar parts.

In general my improved radiator as a whole is made of two or more parts. In the drawings I have shown two parts which are each connected to the engine by separate connections. Each part is composed of a front and a rear section connected together with an air space between them. My object is to provide duplicate means for cooling the cooling water so that each section may be used independently of the other and also to afford by the double system a more efficient means to that end.

40 In the drawings A represents a left hand section of the radiator and B the right hand section. These two sections are separable but in the same vertical plane and are adjacent to each other on the vertical line C. In the rear of these two sections A and B are also two sections D and E having over 45 all substantially the same dimensions as A and B but are, through a portion of the elevation as shown in Fig. 3, narrowed. Sections D and E are placed slightly lower than sections A and B. When the upper 50 and lower edges of sections D and E are placed in contact at H H they leave an opening J between the two sections. The usual

hood K shown in dotted lines in Fig. 1 passes over the radiator and incloses the entire structure, which hood is continued and covers the engine. About this there is nothing new. The foremost sections A and B as represented in section in Fig. 4 are preferably constructed with conical openings L L having their larger ends L' forward and outward and their smaller ends L² inward adjacent to the rear sections D E. 60 As many conical perforations as possible are arranged through the sections A and B, their purpose being to permit air to be forced through when the car to which the radiator is attached is in motion whereby 65 the air is concentrated and thereby increased in density, pressure and velocity in passing from front to rear through said sections A B and thus caused to impinge upon the sections D E respectively. The section A on the one hand is connected to the section D by an inclined water pipe M which passes through section D as shown in Fig. 4, having a comparatively small outlet N into said section. It passes into the section A at N' 70 with a comparatively larger opening so that there is a freer circulation of the rising water passing into section A than that which passes into section D through the opening N. 75 The sections B and E are connected in exactly the same manner and the pipes illustrated at M are connected to the water jacket of the engine in the usual manner. Each of the sections D and E has a filling hole 80 as shown in Fig. 2. The lower part of sections A and B are connected respectively to the sections D and E by a series of small horizontal tubes as shown in elevation Fig. 2 at P P. The water outlet from the radiator to the lower portion of the water jacket 85 of the engine, which is of the usual form, is shown at Q, but each receptacle D and E is connected preferably by a separate pipe at each side of the engine water jacket.

90 It results from this construction that I have two independent systems each exactly alike except they may be rights and lefts so far as the water connections are concerned. These two systems are united in any appropriate manner as by bolts clamping them 95 together as shown at C' and C², C³ Fig. 1 and at C' Fig. 3. It results from this construction that either one of these sections or systems composed of the receptacle A D or B E may be even removed by closing 100 or capping the outlet and inlet ports and the other system may be retained or kept in

operative connection with the engine, and thus repairs may be made to either one of the systems and still the operator would be able to use the other system in the meantime. 5 As these two systems are alike except that they are rights and lefts, it is unnecessary to describe each of them in detail if it be remembered that the connecting pipes M and Q are duplicates and that the two sections A and D or B and E are alike in their features of construction and mode of operation. To describe each of them separately is unnecessary and it is considered that the indicating letters refer to duplicate parts except where otherwise described. 15

The mode of operation of this device taken as a whole is very similar to the ordinary action of the thermosiphon systems, though forcing means might be employed 20 in the shape of pumps or other devices which however form no part of my invention and I do not deem it necessary to describe them.

The mode of operation of this device is 25 quite apparent from the foregoing description but it is sufficient to say that the air being concentrated and driven through the conical perforations L L strikes the flat surfaces adjacent thereto of D and E, is 30 baffled and spread around said surface through the opening J and between the receptacles D and E and the hood thereby creating a very efficient radiating or cooling system. The opening N being restricting 35 ed or choked the heated water in rising through the pipe M will be compelled rise to a higher level in the sections A and B. This also would take place if the sections D and E are filled completely or the flow 40 therein is restricted by compressed air or steam in the top thereof. An outlet is provided in the sections A and B at S whereby if the temperature of the water becomes high enough visible steam will escape and 45 this outlet may be carried above the hood if desired and become an indication of overheating. As the circulation in a thermosiphon system is well known it is unnecessary to describe the operation further. The 50 sections D and E in the arrangement are lower than the sections A and B as will be noted in Fig. 2. A projection T from the bottom of D and E as it were scoops the air and passes it past the connecting pipe P P 55 which air passes through the space J and around the sections D and E at the openings F and G. Arrows indicate the direction of the air currents. While I have shown but two systems it is obvious that by appropriate connections I may make more than 60 two.

What I claim is:

1. In a cooling apparatus for automobile engines, two rectangular radiator sections, 65 each being adapted to form a part of a sepa-

rate water cooling system, said sections being adapted to be removably connected with contiguous edges to form a single radiator.

2. In a water cooling apparatus for automobile engines, the combination of a front 70 receptacle having conical air passages therethrough, the smaller ends of said passages being rearwardly arranged, a second receptacle located at the rear of the first-named receptacle with an air passage intervening 75 therebetween, said second receptacle presenting a cooling surface in the line of flow of air passing through said passages, and adapted to permit the passage of air at one side of said cooling surface. 80

3. In a water cooling apparatus for automobile engines, the combination of a front receptacle having conical air passages therethrough, the smaller ends of said passages being rearwardly arranged, a second receptacle located at the rear of the first-named receptacle with an air passage intervening 85 therebetween, said second receptacle presenting a cooling surface in the line of flow of air passing through said passages, and adapted to permit the passage of air at one side of said cooling surface, said first and second receptacles being so connected that the water shall circulate through both receptacles. 90

4. In a water cooling apparatus for automobile engines, the combination of a front receptacle having conical air passages therethrough, the smaller ends of said passages being rearwardly arranged, a second receptacle located at the rear of the first-named receptacle with an air passage intervening 95 therebetween, said second receptacle presenting a cooling surface in the line of flow of air passing through said passages, and adapted to permit the passage of air at one side of said cooling surface, said first and second receptacles being so connected that the water shall circulate through both receptacles. 100

5. In a water cooling apparatus for automobile engines, the combination of a front receptacle having conical air passages therethrough, the smaller ends of said passages being rearwardly arranged, a second receptacle located at the rear of the first-named receptacle with an air passage intervening 11 therebetween, said second receptacle presenting a cooling surface in the line of flow of air passing through said passages, and adapted to permit the passage of air at one side of said cooling surface, and means for forcing a current of air through the intervening space between said receptacles. 12

6. In a water cooling apparatus for automobile engines, the combination of a front receptacle having conical air passages therethrough, the smaller ends of said passages being rearwardly arranged, a second receptacle located at the rear of the first-named receptacle with an air passage intervening 11 therebetween, said second receptacle presenting a cooling surface in the line of flow of air passing through said passages, and adapted to permit the passage of air 12 at one side of said cooling surface, and means for forcing a current of air through the intervening space between said receptacles, a plurality of passages forming communications between said receptacles and 12 presenting cooling surfaces in said intervening space.

In testimony whereof I sign this specification.

EDWARD T. CURRAN.
